UNITED STATES PATENT OFFICE.

LALLIE TAIT BRAGG, OF CAMDEN, ALABAMA.

CHIMNEY-SUPPORT FOR OIL-LAMPS.

1,297,646.

Specification of Letters Patent. Patented Mar. 18, 1919.

Application filed December 19, 1918. Serial No. 267,420.

To all whom it may concern:

Be it known that I, LALLIE TAIT BRAGG, a citizen of the United States, residing at Camden, in the county of Wilcox and State 5 of Alabama, have invented Chimney-Supports for Oil-Lamps, of which the following is a full and complete specification.

My invention is an improvement in oil-lamps, and has special reference to the provision of means for more securely holding 10 the chimney in connection with the burner.

In the ordinary construction of the conventional oil-lamp the outer edge of the burner device is provided with several spring 15 fingers which grip the lower portion of the chimney for holding it in place on said burner, and unless these fingers embrace the chimney firmly it is likely to be jolted off in handling the lamp. Inasmuch as the 20 chimney must be removed in order to light the burner it is required that the means of connection should be such as to permit its removal and replacement to be accomplished very readily and conveniently, and although 25 the common gripping fingers fulfil this requirement the frequent manipulation of the chimney tends to displace or spread them so that they usually fail to properly grip the chimney and hold it from falling off.

30 It is the purpose of my invention in the present instance to provide the burner device with a marginal annular flange having threads and a shoulder which coöperate with corresponding threads on the lower portion 35 of the lamp-chimney to permit the latter to be more securely connected to said burner, the construction being such that the chimney may be readily applied by giving it a half turn and the threads on the chimney will 40 engage the shoulder in the flange of the burner to securely hold said chimney from working loose or tilting.

In the following specifications I have 45 fully described the construction and operation of the novel means of connection, and what I particularly claim as new, and desire to protect by Letters-Patent is more specifically set forth in the appended claims.

In the drawings:

50 Fig. 1 is an elevation illustrating the application of my invention.

Fig. 2 is a sectional view through the lamp-chimney and coöperating parts of the burner device.

55 Fig. 3 is an elevation of the chimney and

burner, separated, the burner being partly in section.

Fig. 4 is a plan view of the burner device, showing the disposition of the threads.

Like letters and numerals of reference indicate like parts in the several views.

In illustrating the application of my invention I have shown a common form of bowl or font, as A, a conventional type of wick-burner B, and a chimney C of ordinary shape, and as my invention pertains to certain attachments or additions to the chimney and burner the general form of the lamp parts above referred to may be changed, as will be understood.

70 In the present instance the annular plate 5 surrounding the body of the burner is provided with an upwardly projecting marginal flange 6 having internal threads or spiral grooves 7 extending substantially 75 half way around at opposite sides of said flange and opening out at the upper edge thereof, the lower ends of the threads or spiral grooves terminating a distance above the plate 5 to leave an intermediate wall 8 80 between said plate and aforesaid threads. The inner surface of this wall is on a vertical plane with the base of the threads or grooves 7, whereby there is formed a shoulder 9 through which the lower ends of the 85 spiral grooves open out, as will be understood. Of course this particular form of flange may be easily stamped or otherwise shaped from the metal from which the body portion of the burner B is made, and rises 90 from the annular plate 5 to take the place of the gripping fingers heretofore commonly employed.

To coöperate with this marginal flange 95 on the burner device the lower cylindrical portion 10 of the lamp chimney C is provided at opposite sides with threads or spiral ribs 11, 11, corresponding in size and pitch with the threads or spiral grooves 7 in the flange on the burner and preferably 100 starting a short distance above the lower edge of the chimney so that the extreme lower portion of the latter may serve as a guide by entering the annular flange of the burner in advance of the engagement 105 of the threads. The cylindrical portion of the chimney is also extended above the threads or ribs 10 so that the latter may pass beyond the spiral grooves 7 and engage the shoulder 9, the aforesaid cylindri- 110

cal portion of the chimney being then embraced by or fitting within the threaded portion of the flange of the burner and the chimney seated upon the annular plate 5, 5 as clearly shown in Fig. 2 of the drawings.

In attaching the chimney to my improved retaining-flange on the burner the lower end of the chimney is inserted in the upper or threaded portion of the flange and said chimney is then turned to thread the spiral 10 ribs through the corresponding grooves so that the chimney will seat on the annular plate and be securely and firmly held by engagement with the shoulders and threaded 15 portion of said retaining-flange. As will be noted the operation may be readily accomplished, and in this instance the chimney is not only securely connected to the burner but is also prevented from accidentally work- 20 ing loose or falling off. The chimney can be removed as quickly by simply lifting and turning it so as to thread the ribs out of the upper or threaded portion of the retain- 25 ing-flange. As heretofore stated, the chimney retaining-flange will be formed as an integral part of the body portion of the burner by shaping it during the operation of stamping out said body portion from sheet metal, and therefore the complete burner can be 30 produced at less expense than one having the usual spring fingers that have to be applied by a separate operation.

I claim:

1. A burner for oil-lamps having an annular plate and an upwardly projecting marginal flange with threads at the upper portion thereof terminating a distance above the plate, in combination with a chimney having corresponding threads at its lower 40 end and a cylindrical portion above the threads on a vertical plane with the base of said threads, the width of the threaded portion of the chimney corresponding approximately with the width of the space between the annular plate and threaded portion of the burner to fit within said space, substantially as shown and for the purpose set forth.

2. A burner for oil-lamps having an annular plate and an upwardly-projecting marginal flange with threads at the upper portion thereof and a shoulder at the lower

end of the threads through which the latter extend, said shoulder being located a distance above the annular plate of the burner; 55 in combination with a chimney having corresponding threads at its lower end and a cylindrical portion above the threads on a vertical plane with the base of said threads, the width of the threaded portion of the chimney corresponding approximately with the width of the space between the annular plate and shoulder on the burner to occupy 60 said space, substantially as shown and for the purpose set forth.

3. A burner for oil-lamps having an annular plate and an upwardly projecting marginal flange with spiral grooves at its upper portion extending substantially half way around the flange at opposite sides 70 thereof and shoulders between the lower ends of the grooves and at a distance above the annular plate; in combination with a chimney having at its lower end ribs corresponding with the aforesaid grooves and a cylindrical portion above the ribs on a plane with the base thereof, the width of the ribbed portion of the chimney corresponding approximately with the width of the space between the aforesaid shoulders and 80 annular plate of the burner, substantially as shown and for the purpose set forth.

4. A burner for oil-lamps having an annular plate and an upwardly projecting marginal flange with spiral grooves at its upper portion extending substantially half way around the flange at opposite sides thereof and shoulders between the lower ends of the grooves at a distance above the annular plate; in combination with a chimney having a cylindrical portion at its lower end and spiral ribs on said cylindrical portion corresponding with the spiral grooves in the flange of the burner, said ribs being located a short distance above the lower end of the chimney to provide a guiding portion below the ribs, the width of the ribbed portion of the chimney corresponding approximately with the width of the space between the aforesaid shoulders and 95 annular plate of the burner, substantially as shown and described.

LALLIE TAIT BRAGG.
